[57] CLAIM

The ornamental design for a container for displaying
and storing articles, substantially as shown and de-
scribed.

DESCRIPTION

FIG. 1 is a perspective view of a container for displaying
and storing articles showing our new design;
FIG. 2 is a front elevational view thereof;
FIG. 3 is a rear elevational view thereof;
FIG. 4 is a right side elevational view thereof; the oppo-
site side being a mirror image thereof;
FIG. 5 is a top plan view thereof;
FIG. 6 is a bottom plan view thereof;
FIG. 7 is a front elevational view with the top removed
for convenience of illustration;
FIG. 8 is an exploded perspective view thereof;
FIG. 9 is a left side perspective view of a second em-
bodiment of the container for displaying and storing
articles shown in FIG. 1; and
FIG. 10 is a right side perspective view thereof.
